UNITED STATES PATENT OFFICE.

THOMAS JOHN LILLY, OF MONTREAL, QUEBEC, CANADA.

BOTTLE SAFETY HOLDER.

Application filed September 11, 1924. Serial No. 737,173.

To all whom it may concern:

Be it known that I, THOMAS JOHN LILLY, a subject of the King of Great Britain, and residing at the city of Montreal, in the 5 Province of Quebec, in the Dominion of Canada, have invented a new and useful Bottle Safety Holder, of which the following is the specification.

The invention relates to a bottle safety 10 holder, as described in the present specification and illustrated in the accompanying drawings, that form part of the same.

The invention consists essentially of the 15 novel features of construction pointed out broadly and specifically in the claims for novelty following a description containing an explanation in detail of an acceptable form of the invention.

The objects of the invention are to safe 20 guard the contents of bottles containing milk or other fluids and also the bottles themselves in their full state; to afford sanitary precautions in the delivery of milk in bottles; to facilitate the removal of the bottle by the housewife without resorting to 25 keys, latches or other fastenings; to avoid great losses to the milk dealers through the theft of bottles; and generally to provide a simple device within easy reach of the consumer so far as price is concerned and of 30 a durable nature.

In the drawings, Figure 1 is a perspective view of the invention showing a door and door frame, both broken away, and 35 milk bottles in the locking device non-removable therefrom.

Figure 2 is a similar view showing the device open and the milk bottles removable therefrom.

40 Figure 3 is an enlarged cross sectional detail of the device showing the rim of a bottle.

Figure 4 is an enlarged longitudinal sectional view showing the locking spring in 45 engagement with a bottle.

Figure 5 is a longitudinal sectional view showing the bearings and pivot rod.

Like numerals of reference indicate corresponding parts in the various figures.

50 Referring to the drawings, the rim holder 6 is formed of an inverted channel bar having the inwardly curled side walls 7 and 8 adapted to curl around the rim of the bottle sliding therein. The lugs 9, 10 and 11 55 extend from the wall 7 and have the pivot

rod holes 12 through which the pivot rod 13 extends and therebeyond at each end, at one end extending far enough to project through the bearing bracket 14 and at the other end through the bearing bracket 15 60 said rod 13 being fixedly secured in the lugs 9, 10 and 11.

In the mounting the said lugs on the rod 13, the holder 6 is much nearer to one end of the rod than the other, thereby permitting the said rod a sliding movement in the bearing bracket 15 in order to insert the other end of the rod in the bearing 14, which will enable the user to remove the holder, entirely when not required. The bracket 15 65 is secured to the door 16 adjacent to the edge 17, which is at the hinged side secured by the hinges 18. The other bearing bracket 14 is spaced to leave room for the holder 6 between the bearing brackets and some 70 more to insure sliding space for the pivot rod in slipping said rod into its bearings. The door 16 closes the door way formed by the casement 19 and the latter forms a permanent abutment for the rod 13, so long as 75 the door is closed and also a closure for the inner end of the holder 6.

Towards the outer end of the holder the flat spring 20 is secured by the rivet 21 to the holder 6 and extends downwardly and 80 inwardly, so as to snap behind any bottle rim and in from the outer end of said holder.

In the use of this invention the bearing brackets are secured to the door or other 85 closure the requisite distance apart and the holder having the pivot rod attached thereto is first inserted in the bearing bracket near to the casement edge of the door until the rod is far enough beyond the bearing bracket to permit the other end to be inserted in the other bearing bracket.

In this position when the door is closed the end of the pivot rod is adjacent to the casement, in fact so near that it cannot be 90 pulled out from the outer bearing bracket, therefore it is quite safely mounted in its bearings and can only be removed therefrom after the door is open though ordinarily it will be allowed to remain there, still 95 if by any chance it is desirable to remove it during the day or while the residents are absent for a period it can be taken away without removing the bearings or any part of the holder.

To insert a milk bottle the holder is turned upwardly on its pivot and the rim of the bottle inserted in the slideway formed by the inwardly curved side walls and then forced along past the spring, which snaps back behind the bottle rim and locks the bottle in place. The holder may be made long enough to contain several bottles thereby providing, a device which is not confined to holding one or two bottles as it is only limited by the length of the bar. To remove the bottles the housewife simply removes them by pulling through the slideway when the house door is opened for then the casement is well out of the way and offers no obstacle to the removal of the bottle or bottles.

What I claim is:—

A bottle safety holder comprising an inverted channel plate adapted to suspend the bottles therefrom, a plurality of lugs secured to one flange of said plate, and a removable pivot rod adapted to be inserted through said lugs and having its ends projecting beyond the ends of said plate and engaging a pair of bracket bearings rigidly secured to a door adjacent to a casement thereof, said pivot rod adapted to be disengaged from said bracket bearings and said lugs in the open position of said door.

Signed at Montreal, Canada, this 5th day of September, 1924.

THOMAS JOHN LILLY.
